UNITED STATES PATENT OFFICE.

MAX POETZSCH, OF RIDGEWOOD, NEW JERSEY.

COMBINED FINISHING MACHINE FOR PILE FABRICS.

Application filed January 18, 1923. Serial No. 613,462.

To all whom it may concern:

Be it known that I, MAX POETZSCH, a citizen of the United States, and a resident of Ridgewood, in the county of Bergen and State of New Jersey, have invented a new and Improved Combined Finishing Machine for Pile Fabrics, of which the following is a full, clear, and exact description.

This invention relates to a combined finishing machine for pile fabrics and has for an object to produce a structure wherein the finishing or part of the finishing may be done in a more expeditious manner and at a minimum expense.

Another object is to provide a particular form of pile raising machine which may be adjusted readily to produce a pile raising operation to any desired extent, the structure being arranged to readily act on the cloth while the cloth is passing from one machine to another during the process of finishing.

A further object of the invention is to provide a pile raising machine which is so connected up with the power driving members that it may operate at its usual speed ordinarily but may be quickly and easily drawn into extremely slow speed so that the cloth may have a continuous uninterrupted movement at all times.

In the accompanying drawings—

Figure 1 is an outline of several associated devices used in finishing pile fabric.

Figure 2 is an enlarged side view of the pile raising machine shown in Figure 1.

Figure 3 is a top plan view of the pile raising machine shown in Figure 2, the up-standing bracket at the one end being broken off.

Figure 4 is a fragmentary sectional view through Figure 3 approximately on line 4—4.

Figure 5 is a fragmentary sectional view through Figure 3 approximately on line 5—5.

Figure 6 is a fragmentary side view of the lower part of the structure shown in Figure 5, the same illustrating brakes for the tension rollers.

Figure 7 is an enlarged fragmentary sectional view through Figure 5 approximately on line 7—7.

In finishing pile fabric, it is necessary to pass the same through a number of different machines before the complete finished fabric is secured. Part of this finishing

process is the passing of the cloth through a pile preparing machine and also through a pile raising machine, after which it is dried and otherwise treated until complete. 60 Heretofore, these different operations have been carried on more or less independently and at an appreciable cost. As shown in Figure 1, a pile preparing machine, two pile raising machines and a drying machine are shown arranged and associated together to act successively on a strip of fabric from the pile preparing to the drying operation, inclusive. It will be noted from Figure 1 that the fabric is automatically fed from one 65 machine to the other, and consequently, the finishing operation is uninterrupted. 70

Referring to the accompanying drawings by numeral, 11 indicates a pile preparing machine which is provided with tanks 12 and 13. It will be noted that as the strip of fabric leaves the pile preparing machine 11, it is squeezed by the respective squeezing rollers 14 and passes over suitable guide rollers to a guide roller 15 supported on the frame 16 of the pile raising machine 17. From roller 15 the strip of cloth passes over suitable guide rollers 18 and 19 to a spreader 20 and from thence over a supporting roller 21. From the roller 21 the cloth passes above the pile rollers 22 and below the tension rollers 23 to the driving roller 24. From the driving roller 24, the strip of fabric passes over a spreader 25 of any desired construction and from thence between the respective tension rollers 26 and pile rollers 27 to a second driving roller 28. From the driving roller 28, the fabric passes over guide rollers 29 to the guide roller 15 of the next pile raising machine 17. From the pile raising machine 95 25, the fabric passes over suitable guiding rollers to some generally known other finishing machine. It will thus be seen that when the fabric passes through the various machines indicated in Figure 1, it will be prepared, the pile will be raised and the entire fabric may readily pass through other finishing machines.

By the mechanism shown in Figures 2 to 5 inclusive, means have been provided for ordinarily running the fabric through the machine at a normal or high speed and whenever desired, to slow down the speed until it moves very slowly. In producing a construction to carry out this idea and certain others, there are provided driving rollers 24 and 28, driving roller 24 being

driven through the action of a sprocket 31, said sprocket being driven by a chain 32 passing over a sprocket 33, which sprocket is rigidly secured to the shaft 34. The shaft 34 is rigidly secured to a gear 35 meshing continually with a pinion 36, said pinion being rigidly secured to the shaft 37. The shaft 37 (Figure 3) has a clutch member 38 splined thereon operated by a suitable hand 10 actuated lever 39. A high speed pulley 40 is rigidly secured to the shaft 37 by a key or other suitable means and is designed to be driven by a belt, which belt may be shifted to the idler 41 or to the slow pulley 42. When the belt is operating pulley 41, no power is transmitted to the machine, and consequently, the machine stops. If it is shifted to the high speed pulley 40, the machine will operate at its maximum speed but 20 when the belt is shifted to pulley 42, the machine will be operated but at an extremely slow speed. Sometimes slight repairs or adjustments are desired or may become necessary and by reason of the extremely slow 25 speed under which the machine is operating, the desired repairs may be made.

It will be noted that the pulley 42 is keyed to a sleeve 43 and said sleeve is also rigidly keyed to a pinion 44 which pinion continually meshes with a large gear 45. The gear 45 carries a stub shaft 46 to which the pinion 47 is rigidly secured, said last mentioned pinion meshing with a gear wheel 48 rigidly secured to the sleeve 49, which 30 sleeve is loosely mounted on the shaft 37 and which sleeve also is rigidly secured to the clutch member 50, said clutch member co-acting with the clutch member 38. When the power belt is shifted to the pulley 42, 40 lever 39 is moved to bring the clutch members 38 and 50 into engagement whereupon shaft 37 will be driven very slowly and will permit movement of the machine for driving the same very slowly. After the desired repair or adjustment has been accomplished, the pulley may be shifted back 45 to the high speed pulley 40 and the lever 39 moves for disengaging the clutch members. It will be noted that the shaft 37 50 continues to rotate whether the high speed pulley 40 is being driven or whether the slow speed pulley 42 is being driven. Power is transmitted from shaft 37 through pinion 36 to the gear wheel 35 and from thence to the shaft 34. Power is not only transmitted 55 from shaft 34 through the chain 32 and associated parts but also through the respective gears 51 and 52 to the drive roller 28 whereby the cloth is pulled in one direction 60 by the drive roller 24 and pulled in the opposite direction by the drive roller 28.

Mounted on the frame 16 are a plurality of pile raising rollers 22 which are not driven but are permitted to rotate as the 65 fabric is pulled thereover. The pulling of

the fabric over these pile raising rollers will cause the pile to be raised to a great or less extent. To secure desirable results in pile raising, these rollers are prevented from freely rotating and, consequently, there will 70 be a resistance to the rotary movement caused by the movement of the cloth over these rollers. This resistance is caused by providing a brake wheel 54 (Figures 5 and 6) secured to each of the rollers. Each of 75 the brake wheels 54 is provided with a brake band 55 secured at 56 to the frame of the machine while at 57 a threaded tension member is provided whereby any desired 80 braking tension may be secured. In order to hold the strip of fabric against these pile raising rollers, a number of tension rollers 23 are provided, these tension rollers being preferably smooth rollers of any desired kind for holding the clutch against the pile 85 raising rollers. The rollers 23 are preferably staggered in respect to the rollers 22. It will be noted that the pile raising roller 22 will raise the pile as the cloth is pulled by the roller 24 but an independent set of 90 rollers 27 is provided for raising the pile as the cloth is pulled by the roller 28. The rollers 27 are mounted on a vertically adjustable bar 60 and are provided with brakes 61 similar to the brakes shown in Figures 5 95 and 6. This is true of all the rollers 27 except the roller 59' which is driven by a chain 62 passing over a sprocket wheel 63 and over a sprocket wheel 64 secured to the shaft of roller 24. One or more guiding pins 65 are 100 provided at each end of the respective supporting bars 60 for guiding the same in its up and down movement. Also, at each end of the respective bars 60 there is provided a tension screw 66 which is threaded into 105 the bar and presses against an enlargement 67 on the frame 16 whereby the respective bars 60 may be raised and lowered as desired. Each of the tension screws 66 is provided with a notched wheel 68 adapted to be engaged by the spring pressed locking catch 69 for preventing accidental rotation thereof. In the accompanying drawings, four of these tension screws and guiding rods are shown though if desired a greater 110 number could be used.

Co-acting with the pile raising rollers 27 are tension rollers 26 similar to rollers 23 but acting on the upper run of cloth pulled by roller 28. As indicated in Figure 4, the rollers 23 and 26 are mounted on the respective bars 71 and 72, there being two bars 71 and two bar 72, namely, one bar of each kind on each side of the machine. Each pair of bars is provided with a pair of racks 73 and 74 at each end, rack 73 being connected with the bar 72 while rack 74 is rigidly connected with bar 71. A pinion 75 is provided with each pair of rack 115 bars and is positioned in mesh therewith at 120 125 130

all times. A transverse shaft 76 is provided at each end of the machine and rigidly secured to the respective pinions 75. Each of the shafts 76 is provided with a worm gear 77 meshing with the respective worms 78 secured to the shaft 79. The shaft 79 is mounted on suitable brackets carried by the frame 16 and is designed to be operated manually by the hand wheel 80. When the hand wheel 80 is rotated in one direction, the bars 71 and 72 will move apart and when rotated in the opposite direction will move towards each other. When these bars are positioned as shown in Figure 2, the parts are arranged to permit ready setting up of the machine for the first operation. After the cloth has been properly placed into the machine, the bars 71 and 72 are spread apart until a desired tension is provided as indicated in Figure 7. The machine is then started and continually operates until the entire strip has been properly treated.

During the finishing operation, in case it should be desirable to adjust or make repairs on the pile raising machine or on any other finishing machine connected with same, the slow driving mechanism is thrown into operation and, consequently, the parts will move very slowly though the cloth will continue a forward movement. After the repair or desired adjustment has been secured, the high speed driving mechanism is thrown into operation and the parts continue to function as above described. It will be noted that the fabric starts from a suitable pile or supply and first passes, through the pile preparing machine 11 and then immediately through the first pile raising machine 16. The cloth, as indicated in Figure 1, passes by a continuing movement from the first pile raising machine to a second and from the second directly into other finishing machines not subject to these claims.

What I claim is:—

1. A pile raising machine of the character described, comprising a plurality of

pile raising rollers, said rollers being arranged in sets, one set of rollers being movable as a unit toward and from the other, means for adjusting and locking said set of rollers in different positions in respect to the other set of rollers, means for forcing a strip of cloth through the machine so as to be acted on by both sets of rollers, and spreading means for spreading cloth immediately before it approaches the respective set of rollers.

2. A pile raising machine of the character described, comprising an upper and a lower set of pile raising rollers, means for propelling a strip of cloth so that it will pass all of said rollers and the same face will engage said rollers, an upper and lower set of tension rollers co-acting with the pile raising rollers, a supporting frame for each set of tension rollers, a plurality of racks carried by said frames, the racks of one frame extending toward the racks on the opposite frame, a pinion arranged between and meshing with each pair of racks, a shaft carried by each set of pinions, a worm wheel mounted on each of said shafts, a worm meshing with each of said worm wheels, and a manually rotatable shaft connecting said worms so that they will operate in unison whereby when said shaft is rotated in one direction said supporting frames will be moved apart and when rotated in the opposite direction said supporting frames will be moved towards each other.

3. In a finishing machine of the character described, a pile raising apparatus, comprising upper and lower rows of pile raising rollers, means for pulling a strip of cloth in a horizontal plane past the upper row of said rollers, means for pulling said cloth in the opposite direction past the lower row of rollers, and means movable toward and from the respective rows of rollers for holding the cloth in operative position in respect to said rollers.

MAX POETZSCH.
